BAND-PASS SELECTOR

Harold A. Wheeler, Great Neck, N. Y., assignor to
 Hazeltine Corporation, a corporation of Delaware

Application October 22, 1935, Serial No. 46,081

9 Claims. (Cl. 250—20)

This invention relates to modulated carrier signal receivers, and particularly to signal-selecting systems of such receivers and methods of, and means for, controlling the selectivity and fidelity thereof to discriminate against undesired signals.

In radio broadcast systems, a signal is ordinarily transmitted on a carrier frequency, providing two side bands of signal modulation which usually extend 6 kilocycles or more on either side of the carrier frequency. In accordance with present practice, broadcasting stations are allotted carrier frequencies uniformly spaced throughout the broadcast frequency range. The spacing of adjacent carrier frequencies is usually 10 kilocycles and, in many instances, the side-band frequencies of one carrier overlap those of adjacent carriers received at the same location, or closely encroach thereon. By reason of this condition it is frequently difficult to tune a receiver to a desired signal without interference from undesired signals on carrier frequencies near the desired signal carrier, particularly when the strength of such undesired signals is comparable to or exceeds that of the desired signal. In addition to these undesired signals, static and other so-called background noises, which are ordinarily present at the frequencies of the side bands, may interfere with quiet operation.

In order to obtain faithful reception of the desired signal, very nearly free from undesired signal interference and from the static and other background noise, it is necessary to utilize a selecting system effective to pass a band of desired modulation frequencies sufficiently narrow to greatly reduce the undesired signals and noise. Such narrowing of the selected band of frequencies, however, tends to impair the fidelity of reception of the desired signal, since the outer frequencies of the side bands, which in radio broadcasting correspond to the higher audio frequencies of modulation, are suppressed. Accordingly, it is desirable that the width of the selected band of frequencies be contracted only when an undesired signal of sufficient amplitude to cause interference, or noise, is present, and that in its absence the width of the selected band should be expanded sufficiently to admit and pass all of the side-band frequencies of the desired signal.

Various arrangements have heretofore been devised for controlling the expansion and contraction of the band of frequencies passed by a selecting system. In certain of these arrangements, the expansion and contraction of the

band has been automatically controlled in accordance with the amplitude of the desired signal, so that when the desired signal is weak the band passed will be contracted. This manner of control, however, is not wholly satisfactory since, as has been pointed out, the amount of contraction required for optimum reception depends not only on the desired signal intensity but also, and in fact primarily, on the requirements for avoiding interference on the undesired signal frequencies near the desired signal carrier frequency. Even though the desired signal is strong, the undesired signals may be sufficiently strong to require contraction of the band. The undesired signals most likely to cause interference are, naturally, those having carrier frequencies which are separated by only 10 kilocycles from the carrier frequency of the desired signal.

In addition to properly controlling the selectivity of a receiver, in order to obtain faithful reception, it is also necessary to control the amplification in the receiver so that the output thereof will be maintained within a relatively narrow range of amplitude for a wide range of input signal amplitudes. Various well-known arrangements, which are commonly referred to as automatic amplification control, automatic volume control, or A. V. C., have been satisfactorily employed for this purpose. Ideal operation of a modulated carrier receiver, therefore, requires automatic expansion and contraction of the selected band of frequencies according to the amplitude of the undesired signals as well as according to the amplitude of the desired signal, together with the control of the amplification of the signals so as to maintain the output of the receiver within a relatively narrow range of amplitude for a wide range of received signal amplitudes.

It is a primary object of the present invention, therefore, to provide a method of, and means for, automatically controlling the selectivity of a modulated carrier signal receiver to obtain maximum fidelity of reception consistent with the intensity of undesired signals near the desired signal carrier frequency.

It is a further object of the invention to provide a method of, and means for, automatically controlling the selectivity of a modulated carrier signal receiver to obtain maximum fidelity of reception consistent with the relative intensities of the desired signal and undesired signals on frequencies near the desired signal carrier frequency.

It is a still further object of the invention to

provide, in a modulated carrier signal receiver, a method of, and means for, automatically controlling the amplification of signals therein, to maintain the amplitude of the receiver output within a relatively narrow range for a wide range of input signal amplitudes, and for simultaneously automatically controlling the selectivity of the receiver to obtain optimum fidelity permitted by the relative intensities of the desired signal and undesired signals, as above mentioned.

For a better understanding of my invention, together with other and further objects thereof, reference is had to the following description taken in connection with the accompanying drawing, and its scope will be pointed out in the appended claims.

In accordance with a feature of the invention, there is included in a signal-receiving system the combination of means providing two tuned coupled signal circuits, an electronic control device providing a variable impedance across at least one of the circuits, and means for decreasing the impedance of the control device in accordance with increases in the average amplitude of received signals of one frequency band and for increasing the impedance of said control device in accordance with increases in the average amplitude of received signals of frequencies adjacent to the first-mentioned frequency band.

Also in accordance with a feature of the invention, there is provided in a modulated-carrier signal received a band-pass selector for selecting a desired signal comprising a carrier frequency and a band of modulation frequencies. The arrangement includes means for adjusting the width of the band of frequencies passed by the selector, means for automatically controlling the adjusting means to expand and contract the band, respectively, with increasing and decreasing amplitude of the desired signal input to the selector, and means for automatically adjusting the amplitude of the desired signal input inversely in accordance with the amplitude of the input to the receiver of an undesired signal having a carrier frequency near the carrier frequency of the desired signal. By this arrangement, the band is contracted sufficiently substantially to limit the amplitude of the undesired signal output from the selector.

Also in accordance with a feature of the invention, there is provided in a modulated-carrier signal receiver a band-pass selector for selecting a desired signal comprising a carrier frequency and a band of modulation frequencies. In this arrangement, the selector comprises a primary circuit and a tuned secondary circuit coupled thereto and an auxiliary sharply-tuned trap circuit coupled to the secondary circuit. The primary and secondary circuits are coupled by less than optimum coupling and tend to limit the transmission of the selector to a relatively narrow band of frequencies, and the secondary and trap circuits are coupled by considerably more than optimum coupling to expand the band passed by the selector. The arrangement includes means for damping the trap circuit to reduce its effect on the selector and means responsive to the amplitude of an undesired signal on a frequency near the desired signal-carrier frequency for automatically controlling the damping means to adjust the width of the band of frequencies passed by the selector inversely in accordance with the amplitude of the undesired signal.

In the accompanying drawing, Fig. 1 is a cir-

cuit diagram of a complete superheterodyne receiver, partly schematic, employing the present invention; and Figs. 2-5 are graphs representing certain operating characteristics of the receiver to aid in the understanding of the invention, Fig. 2 showing the characteristic of the intermediate-frequency amplifier, Fig. 3 illustrating the characteristics of the adjustable band-pass selector, Fig. 4 representing the resulting extreme conditions obtained in the amplifier as a whole, and Fig. 5 illustrating generally the ultimate results obtained by the present invention.

Referring now more particularly to Fig. 1, there is here shown schematically a superheterodyne radio receiver, employing my invention in a preferred form. In general, the receiver includes a tunable radio-frequency amplifier and frequency changer 7 having its input connected with an antenna 10 and a ground 11 and its output connected to an intermediate-frequency amplifier 8 by means of a band-pass selector system 12 which forms a part of the present invention and is hereinafter described in detail. A selective coupling network 13 serves to couple the output of the intermediate-frequency amplifier 8 to a detector and audio-frequency system 9. The selective coupling network 13 includes an intermediate-frequency transformer 14 having a primary winding 15, which is included in the output of the last stage of intermediate-frequency amplification and is tuned to the intermediate frequency by a condenser 16, and a secondary winding 17, which is included in the input of the detector and audio-frequency system and is tuned to the intermediate frequency by a condenser 18.

The primary circuit of the transformer 14 is damped by parallel resistor 19, and the damping of the primary and secondary circuits is proportioned so that the primary circuit is broadly resonant and the secondary circuit is sharply resonant. The coupling of the transformer is on the order of optimum, preferably somewhat greater than optimum, and the arrangement thus provides a selective quieting action, by reason of the selectivity of the secondary circuit, which is entirely subsequent to the automatic control provided by the present invention as hereinafter described.

It will be understood that the tunable radio-frequency amplifier and frequency changer 7, the intermediate-frequency amplifier 8, and the detector and audio-frequency system 9 may be of conventional construction and operation, the details of which are well known in the art, rendering description thereof unnecessary herein.

Neglecting for the moment the particular operation of the selector systems 12 and 13 and the apparatus associated therewith constituting the principal features of the present invention as described hereinafter, the system described above comprises a conventional modulated-carrier signal receiver of the superheterodyne type for receiving a desired signal comprising a carrier frequency and a band of modulation frequencies. The operation of such a receiver is well understood in the art and a detailed explanation thereof is, therefore, unnecessary. In brief, signals intercepted by the antenna are selected, amplified, and converted to intermediate frequencies, in the well-known manner in the tunable radio-frequency amplifier and frequency changer 7, the intermediate-frequency signals being selected and amplified in the intermediate-frequency amplifier 8. The amplified intermediate-frequency signals are thereupon delivered to the detector and

audio-frequency system 8, wherein the audio-frequency signals are derived, amplified and supplied, in the usual manner, to a loudspeaker for reproduction.

While, in accordance with the present invention, any suitable selectivity control circuit per se may be employed for adjusting the width of the band of frequencies passed by the selector, in the preferred arrangement shown in the drawing, the band-pass selector 12 is provided for this purpose. The selector 12 comprises an intermediate-frequency transformer 20, having a primary winding 21 included in the output circuit of the radio-frequency amplifier and frequency changer 7 and a secondary winding 22 included in the input circuit of the intermediate-frequency amplifier 8. An adjustable fixed condenser 23 is connected across the secondary circuit as illustrated, serving to tune this circuit to the intermediate frequency. Also associated with the transformer 20 is an auxiliary trap or tertiary circuit 24, comprising a winding 25 and condenser 30 for tuning the winding 25 to the intermediate frequency. The coupling between the primary and secondary windings 21 and 22 is considerable but less than optimum and not sufficient to damp the secondary circuit appreciably, so that, independent of the trap circuit, the transmission of a relatively narrow band of frequencies is effected. The secondary winding 22 and tertiary winding 25, however, have a coefficient of coupling considerably greater than optimum, preferably approximately double the ratio of the highest desired frequency of modulation to the intermediate frequency, so that the effect of the trap circuit is to expand the pass band of the selector system to a relatively broad band of frequencies.

In order automatically to control the effectiveness of the trap circuit to expand and contract the pass band thereof, respectively, with increasing and decreasing amplitude of the desired signal input to the selector, and thereby control the selectivity of the system, means are provided for automatically damping the trap circuit. While any suitable arrangement may be employed for this purpose, in the preferred embodiment of the invention a vacuum tube 26 is employed, with its space path connected across the trap circuit, and means are provided, as hereinafter further described, for applying a negative bias voltage to the grid of this tube to control the tube conductance and hence its damping effect on the trap circuit. A suitable voltage source, such as a battery 27, is provided for supplying the space current of the tube 26. The anode and grid of the tube are connected through a coupling condenser 28, and a leak resistance 29 is included in the grid circuit. The condenser 28 and resistor 29 serve to provide a degenerative effect which greatly increases the damping to which the trap circuit can be subjected by the tube. The tube 26, as well as the tubes of the intermediate-frequency amplifier 8, are preferably of the variable-mu type having a gradual cutoff, in order that distortion of the signal envelope may be avoided.

In order to produce the control bias voltage for the tube 26 and for controlling the amplification in the tubes of the intermediate-frequency amplifier, a diode rectifier 31 is coupled to the output circuit of the intermediate-frequency amplifier through coupling condenser 32. An intermediate-frequency choke coil 33 is connected between the cathode and ground. The load circuit

of the rectifier 31 comprises a resistor 35 and a by-pass condenser 34, the bias voltage being built up across this resistor in the usual manner. In order to insure that the biasing voltage be proportional to the intermediate-frequency carrier and unresponsive to the modulation voltages, there is provided, in addition to the condenser 34 and resistor 35, a filter comprising a series resistor 36 and shunt condenser 37 proportioned to have a time constant which is greater than the period of the lowest audio-frequency components of the signal modulation. The bias voltage thus developed is applied in a negative sense to the control grids of the amplifier tubes in the intermediate-frequency amplifier, in the usual manner, to decrease the amplification therein with increasing carrier amplitude of the intermediate-frequency signal input to said amplifier, thereby to maintain the output of the amplifier within a relatively narrow range for a wide range of input amplitudes of the desired signal carrier. The bias voltage across resistor 35 is also applied through a resistor 29 to the control grid of the tube 26 to control the damping of the circuit 24. The effect of the circuit 24 in the selector 12, and hence the selectivity of the receiver, is thus controlled. In other words, expansion and contraction of the width of the band passed by the selector 12 are effected automatically with increasing and decreasing amplitudes, respectively, of the desired signal carrier input to the selective intermediate-frequency amplifier 8.

The amplitude of the desired signal carrier input to the intermediate-frequency amplifier is thus the factor which directly determines the degree of amplification therein and the band width of the selected band. In the absence of undesired signals, this general relation is sufficient for satisfactory reproduction and no other type of control is needed. The arrangements of the prior art, as hereinbefore mentioned, have been based on this relation. In accordance with the present invention, however, means are provided for automatically adjusting the amplitude of the desired signal input inversely in accordance with the amplitude of the input to the receiver of the undesired signal carrier, specifically, for reducing the amplitude of the desired signal carrier input to the intermediate-frequency amplifier with increasing amplitude of an undesired signal on a frequency near the desired signal carrier frequency. Hence, the presence of an undesired signal capable of causing interference will indirectly effect the contraction of the band of frequencies passed by the selector in the same manner as a reduction of the desired signal intensity and the band width is contracted sufficiently substantially to limit the amplitude of the undesired signal output from the selector.

This control by undesired signals is accomplished, in the preferred form of the invention shown in the drawing, by the provision of an auxiliary intermediate-frequency amplifier 38 connected to the output of the frequency changer and having its output, in turn, connected to an automatic volume control or "first A. V. C. rectifier" 39. The radio-frequency amplifier 7 is designed to pass a band of frequencies which is at least as wide as the fully expanded band of the intermediate-frequency amplifier 8, this relation being essential to obtain the full benefit of expansion. The intermediate-frequency amplifier 38, however, is designed to pass a band of frequencies which is substantially wider than that of the radio-frequency amplifier; that is, it

passes and amplifies not only the desired signal but also all undesired signals which are passed by the radio-frequency amplifier and which have sufficient amplitude to be capable of overloading the frequency changer or causing interference. The rectifier 39 is designed and operates in the conventional manner to develop a bias voltage proportional to the amplitude of the signal, supplied thereto. The bias voltage thus developed is applied negatively to the control grids of one or more of the tubes in the radio - frequency amplifier and frequency changer 7 to decrease the amplification therein proportionally to the input of the rectifier 39. Hence, in the presence of interfering signals, the desired carrier input amplitude to the intermediate-frequency amplifier 8 is reduced, with the resultant contraction of the band as previously explained.

The rectifier 39, together with the rectifier 31, thus provide a double automatic volume control, the control by the rectifier 39 serving to keep the signal level well below the overload level in the first part of the receiver, and the control provided by the rectifier 31 serving, as above described, to maintain the amplitude of the input to the detector 8 substantially uniform. By thus avoiding overloading of the receiver, distortion of the desired signal and cross-modulation of the desired signal by undesired signals are obviated. The expanding selector 12 may be repeated in cascade if additional selectivity control is desired. In a high grade receiver, two expanding circuits will probably be used. Since, as before mentioned, the undesired signals which are most likely to cause interference are those separated from the desired signal carrier by about 10 kilocycles or, in other words, are signals on carrier frequencies adjacent the carrier frequency of the desired signal, the intermediate-frequency amplifier 38 in the preferred embodiment of the invention is designed to have a response characteristic such as that illustrated by the curve of Fig. 2, that is, this amplifier is designed to be more responsive on adjacent carrier frequencies than on the desired carrier frequency and other frequencies. In Fig. 2, as also in Figs. 3 and 4, relative gain in decibels is plotted against frequency difference from the intermediate carrier frequency, in kilocycles. By virtue of the characteristic represented in Fig. 2, the adjacent undesired signals have relatively a substantially increased effect; that is, a relatively greater contraction of the band width is effected by these signals. The construction and operation of amplifiers having a characteristic curve such as shown in Fig. 2 is well known by those skilled in the art, and a detailed description thereof is deemed unnecessary.

Referring now to the general operation of the receiver, the curves of Fig. 3 illustrate the effect of the trap circuit on the amplification and band width of the intermediate-frequency selector with which the trap is associated. Curve 38 illustrates the condition when a minimum bias voltage is being applied to the tube 26 as the result of a minimum carrier input amplitude to the amplifier 8. Under these conditions there is a maximum damping of the trap circuit 24 and consequently the band width is fully contracted. Curve 39 illustrates the amplification characteristic corresponding to the opposite conditions, that is, a maximum bias on the tube 26, resulting from a maximum carrier input amplitude

to the amplifier. Under these conditions, there is a minimum damping of the trap circuit, which is the condition for a fully expanded band. The other coupling circuits of the intermediate-frequency amplifier are preferably designed to have sufficient selectivity to flatten the curve 38.

It will be apparent that amplification in the intermediate-frequency amplifier is reduced not only by the action of the bias voltage applied directly to one or more of the amplifier tubes, but also by the action of the trap circuit 24. Thus, the negative bias which is applied to the tube 26 reduces the intermediate-frequency amplification by an amount comparable to the reduction obtained by the control of an amplifier tube. These effects are preferably proportioned to maintain substantially uniform amplification in this amplifier at frequencies 10 kilocycles above and below the intermediate carrier frequency.

Fig. 4 shows the resulting extreme conditions in the over-all response of the intermediate-frequency amplifier and preceding apparatus. The curve 40 represents the condition with a minimum input to the intermediate-frequency amplifier and hence a minimum application of bias voltage to the tube 26 with consequent contraction of the band width, while the curve 41 represents the opposite conditions. An increase in the negative bias voltage developed by the rectifier 31 thus has the effect of flattening the peak of the characteristic curve of the amplifier and proportionally increasing the band width. Hence, it may be said that the amplification of the desired signal in the amplifier is automatically reduced with increasing carrier amplitude of the intermediate-frequency signal input to the amplifier, while the amplification at the two adjacent carrier frequencies 10 kilocycles from the desired signal carrier frequency is maintained substantially unchanged. The amplitude of the input to the amplifier of signals on the adjacent carrier frequencies is automatically maintained within a predetermined limit by the amplification control rectifier and the band is contracted sufficiently to maintain the amplitudes of undesired signal output from the amplifier less than a predetermined small value.

Fig. 5 is a graphical representation of the ultimate results to be obtained by the present invention, the relative intermediate-frequency band width, in kilocycles, being plotted against the relative received signal intensities, in decibels, for three different conditions of reception. Curve 42 corresponds to the condition where no undesired signals capable of causing interference are being received. When the signal intensity is small, the band width is contracted, expansion taking place to a predetermined extent as the signal intensity increases sufficiently above the background noise level. In the presence of strong undesired signals, a much greater signal intensity is required to cause the same amount of expansion. Thus, curve 43 illustrates the operation of the system when an undesired signal of sufficient amplitude to cause interference is being received, while curve 44 illustrates the operation when an undesired signal of still greater amplitude is being received. This constitutes the ideal operation of automatic selectivity control; that is to say, the control circuit performs automatically the same operations as would be performed manually by a skilled operator having all the various properties of the receiver under his control.

The intermediate-frequency amplifier may

advantageously be so designed that the ratio of the peaks to the valleys in Fig. 2 is about 20 decibels. Increasing this ratio causes further reduction of expansion of the band width in the presence of undesired signals, with corresponding further reduction of interference. A representative range of expansion is one and one-half octaves, corresponding to band widths from 5 to 14 kilocycles. In terms of audio-frequency output of the receiver, this corresponds to upper cut-off frequencies of from 2500 to 7000 kilocycles.

In summary, therefore, it is seen that by the arrangement of Fig. 1 there is included, in a signal-receiving system, the combination of means providing two tuned coupled signal circuits 25, 30 and 22, 23 and an electronic control device 26 providing a variable impedance across at least one of the circuits, specifically, across tuned circuit 25, 30. The arrangement comprises means including rectifier 31 for increasing the impedance of the control device 26 in accordance with increases in the average amplitude of received signals of one frequency band, specifically, in accordance with the desired frequency band, and for increasing the impedance of the control device in accordance with increases of the average amplitude of received signals of frequencies adjacent to the desired frequency band.

While the invention has been described as employed in connection with a receiver designed for the reception and reproduction of a carrier and both side bands of modulation frequencies, it will be readily appreciated that the essential features of the invention are equally applicable to receivers designed for signal side-band reception, for example, such as the receivers described in Patents 2,050,679 and 2,050,680 granted to applicant on August 11, 1936. The features of this invention are also particularly well adapted for use in connection with the receiving systems disclosed in Patent 2,054,412 granted to John F. Farrington on September 15, 1936; Patent 2,038,358 granted to Daniel E. Harnett on April 21, 1936; and Patent 2,073,344 granted to John Kelly Johnson on March 9, 1937. For such a receiver, the circuits embodying the present invention will be designed accordingly for properly adjusting the width of the single side band which is passed. The invention thus contemplates means for adjusting at least the width of the part of the selected band on one side of the desired carrier frequency inversely in accordance with the input amplitude of an undesired signal on a frequency near said band and on the same side of the carrier frequency.

While I have described what I at present consider the preferred embodiment of my invention, it will be obvious to those skilled in the art that various changes and modifications may be made therein without departing from my invention, and I, therefore, aim in the appended claims to cover all such changes and modifications as fall within the true spirit and scope of my invention.

I claim:

1. In a modulated carrier signal receiver, a band-pass selector for selecting a desired signal comprising a carrier frequency and a band of modulation frequencies, means for adjusting the width of the band of frequencies passed by said selector, means for automatically controlling said adjusting means to expand and contract said band respectively with increasing and decreasing am-

plitude of the desired signal input to said selector, and means for automatically adjusting the amplitude of said desired signal input inversely in accordance with the amplitude of the input to said receiver of an undesired signal having a carrier frequency near the carrier frequency of said desired signal, whereby said band is contracted sufficiently to substantially limit the amplitude of the undesired signal output from said selector.

2. In a modulated carrier signal receiver, a band-pass signal amplifier for amplifying a desired signal comprising a carrier frequency and a band of modulation frequencies, means for varying the signal amplification in said amplifier inversely in accordance with the amplitude of the desired signal carrier input to said amplifier to maintain the output thereof within a relatively narrow range for a wide range of input signal amplitude and for simultaneously adjusting the width of the band of frequencies passed thereby, directly in accordance with the amplitude of the desired signal carrier input to said amplifier, and means for automatically adjusting the amplitude of said carrier input inversely in accordance with the amplitude of the input to said receiver of an undesired signal on a frequency near said band, said means being mutually proportioned to contract the width of said band automatically sufficiently to maintain the amplitude of said undesired signal less than a predetermined small value in the output of said amplifier.

3. In a modulated carrier signal receiver, a band-pass signal amplifier for selecting a desired signal comprising a carrier frequency and a band of modulation frequencies, means for varying the signal amplification in said amplifier inversely in accordance with the amplitude of the desired signal carrier input to said amplifier to maintain the output thereof within a relatively narrow range for a wide range of input signal amplitude and for simultaneously adjusting the width of the band of frequencies passed thereby directly in accordance with the amplitude of the desired signal carrier input to said amplifier, and means substantially more responsive at frequencies near the desired signal carrier frequency and other frequencies, for automatically adjusting the amplitude of said carrier input inversely in accordance with the amplitude of an undesired signal on a frequency near said band, said means being mutually proportioned to contract the width of said band automatically sufficiently to maintain the amplitude of the undesired signal less than a predetermined small value in the output of said amplifier.

4. In a modulated carrier signal receiver, a band-pass selector for selecting a desired signal comprising a carrier frequency and a band of modulation frequencies, said selector comprising a primary circuit and a tuned secondary circuit coupled thereto, and an auxiliary sharply tuned trap circuit coupled to said secondary circuit; said primary and secondary circuits being coupled by less than optimum coupling and tending to limit the transmission of the selector to a relatively narrow band of frequencies, and said secondary and trap circuits being coupled by considerably more than optimum coupling to expand the band passed by the selector, means for damping the trap circuit to reduce its effect on said selector, and means responsive to the amplitude of an undesired signal on a frequency near the desired signal carrier frequency for automatically controlling said damping means to adjust

the width of the band of frequencies passed by said selector inversely in accordance with the amplitude of said undesired signal.

5. In a modulated carrier signal receiver, a band-pass selector for selecting a desired signal comprising a carrier frequency and a band of modulation frequencies, said selector comprising a primary circuit and a tuned secondary circuit coupled thereto, and an auxiliary sharply tuned trap circuit coupled to said secondary circuit; said primary and secondary circuits being coupled by less than optimum coupling and tending to limit the transmission of the selector to a relatively narrow band of frequencies, and said secondary and trap circuits being coupled by considerably more than optimum coupling to expand the band passed by the selector, a vacuum tube conductance connected across said trap circuit for damping said trap circuit to reduce its effect on said selector, means for developing a bias voltage having an amplitude varying directly with the input carrier amplitude of the desired signal, means for negatively applying said voltage to a control electrode of said vacuum tube conductance whereby the width of the band of frequencies passed by said selector is adjusted, and means for modifying said input carrier amplitude inversely in accordance with the amplitude of an undesired signal on a frequency near the desired signal carrier frequency.

6. A radio receiving system having a plurality of cascade-coupled amplifiers and including means for altering the selectivity thereof in one sense in response to variations in the amplitude of a potential derived from electrical energy in a limited range of frequencies and in the opposite sense in response to variations in the amplitude of a potential derived from electrical energy in frequency bands adjacent to said limited range, in which said means comprise an impedance connected substantially in parallel with at least one of the coupling devices of said amplifiers and means controlled by said potentials for varying said impedance in opposite sense.

7. A radio receiving system having a plurality of cascade-coupled amplifiers and including

means for altering the selectivity thereof in one sense in response to variations in the amplitude of a potential derived from electrical energy in a limited range of frequencies and in the opposite sense in response to variations in the amplitude of a potential derived from electrical energy in frequency bands adjacent to said limited range, in which said means comprise at least one coupling device for at least two of said amplifiers, said coupling device including two tuned circuits intercoupled, an electronic control device providing variable impedance means connected in parallel with at least one of said tuned circuits, and means for applying said control potentials to said variable impedance means to cause the impedance thereof to vary and thereby to alter the selectivity of said coupling device in opposite sense.

8. In a radio receiving system, the combination of a plurality of electronic amplifier devices, coupling means between at least two of said devices comprising a pair of coupled resonant circuits, an electronic control device connected in parallel with one of said resonant circuits, and means for impressing control potentials on said control device in response to received signals in a desired band of frequencies and in response to received signals in at least one frequency band adjacent to said desired band in opposite sense and in a direction to vary the selectivity of said system through said coupling means directly with the impedance of said control device.

9. In a signal receiving system, the combination of means providing two tuned coupled signal circuits, an electronic control device providing a variable impedance across at least one of said circuits, and means for decreasing the impedance of said control device in accordance with increases in the average amplitude of received signals of one frequency band, and for increasing the impedance of said control device in accordance with increases in the average amplitude of received signals of frequencies adjacent to said first mentioned frequency band.

HAROLD A. WHEELER.
